RAYMOND A. HEISING, OF MILBURN, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed December 22, 1920, Serial No. 432,444. Renewed November 20, 1924.

This invention relates to signaling systems, and more particularly to systems employing electron discharge devices as amplifiers and modulators.

In the well-known application of three-electrode electron discharge devices as amplifiers, it has been the general practice heretofore to maintain the grid or impedance controlling element at all times at a negative potential with respect to the cathode or heated filament, if such be used. Likewise, when such a device has been used as a modulator wherein carrier waves of constant amplitude may be modulated by current of signaling frequency, the potential of the grid has heretofore been maintained negative. In each of these cases the grid has been maintained at a negative potential in order that none of the electrons emitted by the cathode might pass to the grid and so reduce the otherwise very high input impedance of the device. Due to this high input impedance, a negligible amount of energy was consumed in the input impedance; but to maintain this condition during operation, the amplitude of the impressed voltage was necessarily limited.

When using electron discharge devices in the manner just described, it has been customary to connect a very high impedance, for example a resistance of the order of one-half a megohm or more, across the input terminals of the amplifier or modulator tube and to connect a secondary of a speech transformer to this resistance.

According to this invention the grids of the discharge devices are allowed to become positive, thereby increasing the allowable impressed voltage amplitude. It has been found that a maximum of energy can be obtained in the output circuit of the discharge devices with a minimum of distortion of the signaling wave by providing an impedance across the secondary of the speech transformer and the input circuit of the discharge devices of approximately the value of the positive grid impedance. This impedance may take the form of a substantially pure resistance.

When large amounts of power are obtained from an electron discharge device, such as an amplifier or a modulator by allowing the peaks of the input voltage waves to make the grid positive with respect to the cathode, current flows from the grid to the cathode as soon as the grid becomes positive. Under this

condition, the input circuit of the discharge device has a finite resistance which is often quite low. The input impedance of such a device supplying large amounts of power may, therefore, be large over most of a signal cycle (say 500,000 ohms for 300 degrees) and fall to a low value during the rest of the cycle (say 12,000 ohms for 60 degrees). If the circuit working into the grid is a high impedance circuit, it will produce proper potentials for the 300 degrees of the cycle, but during the remaining 60 degrees the impedance of 12,000 ohms will practically act as a short circuit therefor. Distortion of the signal results, due to the fact that the positive potentials corresponding to the signal, are not faithfully reproduced and impressed upon the grid. To prevent such distortion, means must be provided to maintain the desired voltage across the low 12,000 ohms internal impedance as well as across the high internal impedance of the discharge device during the two parts of the cycle. The input circuit impedance external of the discharge device should, therefore, not be high (500,000 ohms) but should be low (12,000 ohms or lower), in order that it may supply sufficient current to the grid without excessive potential drop therein, to maintain on the grid the desired positive potential in spite of the current which flows. A circuit thus proportioned will give greater output with less distortion than is the case for high impedance input circuits. Distortion, due to current flow in the internal input circuit path, approaches zero as the impedance of the input supply circuit external of the discharge device is made to approach zero. For high grade tone quality and articulation of repeated or modulated voice current, it has been found sufficient to make the impedance of the connected line or supply circuit below and to the left of points 31, 32 of the same order of impedance as the minimum internal impedance between the grid and cathode reached during that part of the signal cycle when the grid is positive with respect to the cathode. A low resistance thus placed in parallel with the grid input circuit prevents the impedance of the supply circuit from varying so widely (500,000 to 12,000 ohms) during the cycle. The supply circuit is then proportioned accordingly.

In a radio transmitting system embodying this invention, an electron discharge or vac-

uum tube modulator supplies energy to an antenna. A source of sustained oscillations and a source of modulating or signaling current are each adapted to supply energy to the modulator. The modulating current may be supplied through an amplifier, the output circuit of which is connected to the input circuit of the modulator through a step-down transformer, across the secondary of which 10 may be connected an impedance substantially equal to the input impedance of the modulator tube at signaling frequencies when the grid is at a positive potential. This impedance, in practice, may be a substantially pure 15 resistance of the order of 12,000 ohms. Resistance values of 500 to 50,000 ohms have been used.

One embodiment of the invention will now 20 be described in detail in connection with the accompanying drawing. Fig. 1 of the drawing illustrates one arrangement of a radio 25 signaling system. The dotted lines indicate a transmission line such as an ordinary telephone or telegraph line, or a connection to a power transmission line which may be substituted for the antenna. Fig. 2 shows a circuit arrangement which may be substituted for a part of the circuit of Fig. 1.

Referring now to Fig. 1, the modulator M 30 supplies energy to an antenna A. A generator of sustained oscillations O, and a speech frequency circuit S, are adapted to supply energy to the modulator M.

Modulator M, as shown, may comprise a 35 plurality of three electrode thermionic vacuum tubes, having filaments 5, 5, anodes or plates 6, 6 and impedance controlling elements or grids 7, 7. The filaments may be heated by a battery 8, while the amount of 40 filament current is controlled in the well-known manner by a variable resistance 9. Energy for the plate circuit is supplied by a source of unidirectional current 10. The plate circuit of the modulator may be coupled 45 to the antenna A through a transformer 11.

The generator O may also comprise a three 50 electrode thermionic vacuum tube of any well-known type. As illustrated, it comprises a filament 12 heated by battery 13 through a controlling resistance 14. The plate circuit is supplied with energy by a unidirectional source 15. The plate circuit and grid circuit are coupled together and to the input circuit of the modulator M through a transformer 16. The frequency of the generated oscillations are determined by the tuned circuit comprising the primary windings of transformer 16, and the condensers 17 and 18.

The speech frequency circuit S may 55 comprise a microphone 19 adapted to impress current upon the input circuit of the modulator M through transformers 21 and 22, thermionic vacuum tube amplifier SA and step-down auto transformer 23. Energy for the microphone may be supplied by battery

20. Transformer 21 may be an induction coil well known in the art; while transformer 22 may be of the step-up type, in order to transform the energy of low potential from the microphone circuit to energy of high potential suitable for impressing upon the input 70 circuit of the speech amplifier SA. A high resistance 24 is also connected across the input of the speech amplifier SA. Battery 25 serves to maintain the grid 26 at a negative 75 potential at all times with respect to the filament 27. Battery 28 supplies energy to the plate circuit of the speech amplifier through an impedance coil 29, in a well-known manner. By this method of connecting a microphone 19 to a speech amplifier SA, a large amount of energy of undistorted wave shape is made available at the output terminals 33, 34 from a limited amount of energy supplied by the microphone. Such an arrangement 80 is not new.

According to this invention there is connected across the secondary circuit of the step-down autotransformer 23 a resistance 30. This resistance is of the order of 12,000 ohms, 90 and its value is so chosen that it substantially matches the input impedance of the modulator M measured across the terminals 31, 32 when the grids 7, 7 are at a potential positive with respect to the filaments 5, 5. The primary of the autotransformer 23 is connected to the output of the speech amplifier SA at the terminals 33, 34.

Condenser 35 serves as a path for oscillations from generator O around the transformer 23 and the resistance 30. Condenser 36 provides a high frequency path around battery 38, which serves to place a certain negative potential on the grids of the modulator M, or condenser 36 may act as a storehouse of 100 negative potential, if it is provided with a leak resistance (not shown), due to grid current. The secondary of the transformer 16 being of relatively low reactance offers little 105 impedance to the current of signaling frequency.

During operation, voltage both from the generator O and the speech frequency circuit S are impressed upon the input circuit of the modulator M. By the well-known action of the modulator M, carrier oscillations modulated in accordance with signaling current are transmitted through the transformer 11 to the antenna A. During such operation the potential of the grids 7, 7 become positive, 115 and as is well known under those conditions, the otherwise almost infinite impedance of the tube is materially reduced. In order to utilize this reduced input impedance efficiently, and to obtain a maximum of energy in the 120 output circuit of the modulator M, this lowered input impedance of the tube has been matched by a substantially equal external impedance such as the resistance 30. In this 125 way it has been found that a larger amount 130

of energy can be obtained in the output circuit of the modulator M, with a minimum of distortion of the signaling wave, than has heretofore been possible.

5 In place of the step-down autotransformer 23 and impedance 30, the step-down transformer 37 of Fig. 2, with the impedance 30 connected across its secondary winding may be connected to the primary terminals 33, 34, 10 and secondary terminals 31, 32. The operation is not changed by this modification, and therefore no further description is necessary.

It is to be understood that this invention is not confined to radio signaling systems, nor 15 in fact to signaling systems employing sustained oscillations as carrier waves. It may find application wherever signaling waves are imposed upon amplifiers or modulators, especially where a thermionic vacuum tube is 20 used for the purpose of amplification or modulation.

To those skilled in the art, other embodiments of this invention will be apparent. All such embodiments, as defined by the appended 25 claims, come within the scope of this invention.

What is claimed is:

1. A thermionic vacuum tube, an impedance 30 controlling element and a cathode for said tube, an input circuit comprising said impedance controlling element and said cathode, a source of signaling current adapted to impress a voltage on said input circuit which causes the impedance controlling element to 35 become positive with respect to the cathode during operation, and an impedance connected across said input circuit of value substantially the same as that of the input impedance of said tube when said impedance controlling element is positive.

2. In a carrier wave signaling system, a modulator, an input circuit for said modulator including a cathode and an impedance controlling element, a source of carrier waves and 45 a source of modulating waves associated with said input circuit, said waves having an amplitude of such value as to cause said impedance controlling element to become positive with respect to the cathode during operation, 50 and means to cause the impedance of said source of modulating waves to substantially equal the minimum impedance of said input circuit due to the impedance controlling element becoming positive.

55 3. In a signaling system, a three electrode thermionic vacuum tube, an input circuit comprising the grid and cathode of said tube, an alternating current source connected to said input circuit, current from said source having an amplitude of such value as to cause said grid to go positive with respect to said cathode, and an impedance connected across said input circuit of value substantially matching the positive grid and cathode impedance.

60 4. In a signaling system, a three electrode

thermionic vacuum tube, an input circuit comprising the grid and cathode of said tube, an alternating current source connected to said input circuit, current from said source having an amplitude of such value as to cause 70 said grid to go positive with respect to said cathode, and an impedance connected across said input circuit of value not substantially greater than the positive grid to cathode impedance. 75

5. The method of operating an electron discharge device having a grid and cathode, which method comprises supplying the grid circuit of the electron discharge device with alternating current impulses of values sufficient to make the potential of said grid positive with respect to said cathode, and compensating for the loss occasioned by the consumption of energy in said grid circuit due to the potential of said grid becoming 85 positive with respect to its cathode.

6. A supply circuit adapted to supply electrical impulses, an electron discharge device connected to said supply circuit and comprising a cathode, an anode, and a control electrode, the magnitude of the impulses supplied by said supply circuit being sufficient to make said grid positive at times with respect to said cathode, the control electrode circuit exterior to said discharge device having an impedance of the order of the impedance between said control electrode and said cathode when said control electrode is at a positive potential. 90

7. A supply circuit adapted to supply electrical impulses, an electron discharge device, means reactively connecting said discharge device to said supply circuit, said discharge device having a control electrode and a cathode, the magnitude of the impulses of said supply circuit being sufficient to make the potential of said control electrode at times positive with respect to said cathode, and means on the input side of said discharge device for reducing the distortion of the wave 110 when said grid is positive with respect to said cathode. 105

8. The combination of an alternating current supply circuit, an electron discharge device connected thereto, a second electron discharge device, a grid, a cathode and an anode for each of said devices, a coupling between said devices, said coupling having an impedance substantially matching the impedance value of the grid circuit of said second 115 mentioned discharge device under the condition that the grid of said circuit is at a positive potential. 120

9. In a signaling system, an electron discharge device, an input circuit for said device 125 including a grid and cathode, a source of input energy adapted to cause the grid to become positive with respect to the cathode during operation, and an impedance connected across said input circuit of value sub-

stantially the same as that of the input circuit of said tube when the grid is positive.

10. In combination, a speech frequency circuit, an electron discharge device, a grid and a cathode for said device, a speech frequency transformer connected between said speech frequency circuit and said grid and cathode, means for causing said grid to have a positive potential with respect to said cathode, and an impedance connected across the discharge device side of said transformer of a value not substantially greater than the impedance between said grid and said cathode when said grid is at its greatest positive potential.

11. In combination, a speech frequency circuit, an electron discharge device, a grid and a cathode for said device, a speech frequency transformer connected between said speech frequency circuit and said grid and cathode, means for causing said grid to become positive with respect to said cathode, and an impedance connected across the discharge device side of said transformer of value substantially equal to the impedance between said grid and cathode when said grid is at a positive potential.

12. In combination, a speech frequency circuit, an electron discharge device, a grid and a cathode for said device, the internal impedance between said grid and cathode varying between limits of the order of 12,000 and 500,000 ohms dependent upon the potential of said grid with respect to said cathode, a speech frequency transformer connected between said speech frequency circuit and said grid and cathode, means for causing said grid to become positive with respect to said cathode, and a resistance of the order of 12,000 ohms connected across the discharge device side of said transformer.

13. In a signaling system, a source of oscillations, a source of signaling current, means to modulate said oscillations in accordance with said signaling current comprising an electron discharge device having a grid and a cathode, the impressed potential from said source of signaling current being of sufficient magnitude to cause said grid to become positive with respect to said cathode, and an impedance connected across said source of signaling current of value substantially equal to that of the impedance between said grid and cathode when said grid is at a positive potential.

14. In a signaling system, a source of oscillations, a source of signaling current, means to modulate said oscillations in accordance with said signaling current comprising an electron discharge device having a grid and a cathode, means to cause said grid to become positive with respect to said cathode, and an impedance connected to said last mentioned means between said means and said discharge device of value substantially equal

to that of the internal impedance between said grid and cathode when said grid is at a positive potential.

15. In a signaling system, an electron discharge device having a grid and cathode, the internal impedance between said grid and cathode varying between limits of the order of 12,000 and 500,000 ohms dependent upon the potential of said grid with respect to said cathode, an input circuit for said device including said grid and cathode, a source of signaling current, a signaling current amplifier, a step-down transformer adapted to receive energy from said amplifier and to supply said energy to said input circuit, and a resistance of the order of 12,000 ohms connected across the low impedance side of said transformer.

16. In an electrical system, an electron discharge device having a grid and a cathode, an input circuit for said device including said grid and said cathode, a source of alternating current, an amplifier for said current, energy translating means connected between said input circuit and said amplifier adapted to receive energy of high potential from the amplifier and to supply energy of a lower potential to said input circuit, said translating means having an effective shunt impedance for said input circuit of value substantially the same as that of the input impedance of said device when its grid is at a positive potential.

17. In an electrical system, an electron discharge device having a grid and a cathode, an input circuit for said device comprising said grid and cathode, a source of alternating current associated with said input circuit, current from said source being of such amplitude as to cause the potential of the grid to become alternately positive and negative with respect to the cathode, and an impedance connected across said input circuit of value not substantially greater than the grid-cathode impedance of said device when the grid is at its maximum positive potential.

18. In an electrical system, an electron discharge device having a grid and a cathode, an input circuit for said device including said grid and cathode, a source of alternating current, means to connect said source of alternating current to said input circuit, whereby the potential of said grid with respect to said cathode is rendered positive, and means associated with said connecting means to cause the maximum positive and negative alternating potentials impressed upon said grid to be substantially numerically equal.

19. In an electrical system, an electron discharge device having a grid, a cathode, and an anode, an input circuit for said device including said grid and cathode, an output circuit for said device including said cathode and anode, a source of alternating current, means to connect said source of alternating current

to said input circuit, said source being of intensity such that the potential of said grid with respect to said cathode is at times rendered positive, and means connected across 5 said input circuit to cause the component of current in the output circuit corresponding to the impressed alternating current to have positive and negative amplitudes relatively proportional to the positive and negative amplitudes of the impressed alternating current. 10

20. In an electrical translating system comprising an electron discharge device having an electron emitting cathode, an impedance controlling element and an anode, the method

15 which comprises impressing alternating current potential upon said cathode and imped-

ance controlling element to cause said element to become positive with respect to said cathode to translate large amounts of power and distributing said power waves so as to prevent distortion thereof due to said impedance controlling element becoming positive. 20

21. A thermionic amplifier combined with means for preventing inherent oscillations therein, including a high reactance and a condenser and a resistance in multiple shunted across the filament-grid circuit. 25

In witness whereof, I hereunto subscribe my name this 17th day of December A. D., 1920.

RAYMOND A. HEISING.
